Primary Examiner — Sanjeev Paul*Assistant Examiner* — Rene H. Kadoo(74) *Attorney, Agent, or Firm* — Banner & Witcoff, Ltd.(57) **CLAIM**

The ornamental design for a handle for a kitchen appliance as shown and described.

DESCRIPTION

FIG. 1 is a front perspective view of a handle for a kitchen appliance showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken line showing of the elements on the rear surface of the handle mounts forms no part of the claimed design.
